US00D735310S

(12) **United States Design Patent**
Drew

(10) **Patent No.:** **US D735,310 S**
(45) **Date of Patent:** **** Jul. 28, 2015**

(54) **AIR FILTER**

- (71) Applicant: **Briggs & Stratton Corporation**,
Wauwatosa, WI (US)
- (72) Inventor: **Christopher J. Drew**, West Allis, WI
(US)
- (73) Assignee: **BRIGGS & STRATTON
CORPORATION**, Wauwatosa, WI (US)
- (**) Term: **14 Years**
- (21) Appl. No.: **29/451,695**
- (22) Filed: **Apr. 5, 2013**

Related U.S. Application Data

(57) **CLAIM**

I claim the ornamental design for an air filter, as shown and described.

DESCRIPTION

FIG. 1 is a front perspective view from above the claimed design;

FIG. 2 is a top plan view thereof;

FIG. 3 is a bottom plan view thereof;

FIG. 4 is a front elevation view thereof;

FIG. 5 is a rear elevation view thereof;

FIG. 6 is a right side elevation view thereof; and,

FIG. 7 is a left side elevation view thereof.

1 Claim, 5 Drawing Sheets
